UNITED STATES PATENT OFFICE.

EARL L. BLASIER, OF KALISPELL, MONTANA.

THRASHING MACHINE.

Application filed November 1, 1923. Serial No. 672,171.

To all whom it may concern:

Be it known that I, EARL L. BLASIER, a citizen of the United States, residing at Kalispell, in the county of Flathead and State of Montana, have invented certain new and useful Improvements in Thrashing Machines; and I do declare the following to be a full, clear, and exact description of the invention, such as will enable others skilled in the art to which it appertains to make and use the same.

In thrashing machines of the types now commonly used, considerable bunching of straw takes place as it is received upon the vibrating straw rack, from the thrashing cylinder and hence difficulty is encountered in properly spreading the straw over the rack to insure separation of all grain therefrom. Also, one of the most serious problems to be dealt with, in the ordinary thrashing machine, is the accumulation of dust, particularly under the cylinder. Such accumulations repeatedly cause explosions, often severely injuring the machine and its attendants or operators.

It is the object of my invention to overcome the difficulties above pointed out, by the provision of air-blowing means having an inlet communicating with the interior of the thrashing machine housing, and a rearwardly directed outlet. Thus, the air drawn in by the air-blowing means, carries all dust with it and such dust cannot therefore accumulate, but travels on through the machine to its outlet end. The blast of air from the outlet of the air-blowing means, serves to direct the straw upwardly and rearwardly before it is dropped upon the straw rack, thus disintegrating the straw to a large extent and permitting the grain to drop freely to the usual grain pan or conveyor, the straw being then deposited loosely upon the rack to be further acted upon by the latter.

With the foregoing in view, the invention resides in the novel subject matter hereinafter described and claimed, the description being supplemented by the accompanying drawing, in which Fig. 1 is a longitudinal sectional view, partly in elevation, of a thrashing machine embodying my improvements, and Fig. 2 is a vertical sectional view taken on the line A—A of Fig. 1.

In the drawing above briefly described, the numeral 1 designates the housing of a thrashing machine, in one end of which the

usual cylinder 2 is transversely disposed. Under the cylinder 2, concaves 3 are illustrated, and behind these concaves, a pair of rearwardly inclined grates 4 and 5, have been shown. Adjacent the upper end of the grate 5, a straw beater 6 is illustrated, beyond this beater, a transverse straw check 7 is shown extending downwardly from the top of the housing, and in the lower portion of this housing, the straw rack 8 has been illustrated with its front end spaced downwardly from the grate 5.

In the space between the straw rack 8 and the grates 4 and 5, I have shown an elongated fan casing 9 which is of cylindrical form in the present disclosure, said casing being mounted in the housing 1 in any desired manner, for instance, upon suitable supports such as that indicated at 10. The ends of the casing 9 are open to receive air and dust sucked from the interior of the housing 1, in the vicinity of the cylinder 2, and the distance between these open ends, is substantially the same as the length of said cylinder. The upper portion of the casing 9 is provided with a rearwardly inclined discharge neck 11 which may well have an adjustable lip 12.

Suitably mounted within the casing 9, is a combined air suction and blowing fan 13, driven in any desired manner. It will be obvious that when this fan is operating, air will be drawn into the casing 9 from the interior of the housing 1 and that this air will carry with it any prevailing dust, instead of permitting said dust to accumulate and later explode. This air and any dust which may be therewith, is discharged upwardly and rearwardly through the neck 11, so that the straw thrown rearwardly from the cylinder 2, is also forced upwardly. In acting upon the straw in this manner, the air loosens such straw and permits the grain to readily fall therefrom, before the straw reaches the straw rack 8. Furthermore, bunching of the straw on the front end of the rack is prevented, by the air blast.

As excellent results may be obtained from the general association and construction shown, they are preferably followed, but within the scope of the invention as claimed, numerous minor changes may be made.

I claim:

In combination in a thrashing machine, a rotary thrashing cylinder, co-operating stationary thrashing concaves located under

said cylinder, a stationary grate located under said cylinder in rear of said concaves, said grate being provided with air and dust passages, a fan casing located under the 5 rear portion of said grate and having open ends in communication with the portion of the interior of the machine beneath said grate to suck the air and dust through said passages, a fan mounted in said casing.

and a rearwardly and upwardly directed 10 discharge spout carried by said casing to discharge the air and dust sucked by said fan rearwardly and upwardly beyond the rear end of said grate.

In testimony whereof I have hereunto 15 affixed my signature.

EARL L. BLASIER.
